UNITED STATES PATENT OFFICE.

CHARLES F. STODDARD, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

1,031,742.

Specification of Letters Patent.

Patented July 9, 1912.

Application filed July 25, 1908. Serial No. 445,291.

To all whom it may concern:

Be it known that I, CHARLES F. STODDARD, of Dorchester, Boston, in the county of Suffolk and State of Massachusetts, have ⁵ invented certain new and useful Improvements in Pneumatic-Despatch-Tube Apparatus, of which the following is a specification.

My invention relates to pneumatic ¹⁰ despatch tube apparatus and especially to those of small bore such as are used in stores for carrying cash, etc.

The object of this invention is to produce a system simple in construction and economical in operation. The system here described and shown is operated by exhaustion, but the invention would apply equally well to a system operated by pressure.

In the economical operation of a ²⁰ pneumatic tube system, it is advantageous to shut off the flow of air through the tubes when they are not conveying carriers, because the largest part of the power required to operate a system is used to propel the air ²⁵ through the tubes, and not, as might be ordinarily supposed, to drive the carriers. It is a well-known fact that the longer the tube the more power is required to drive the air at a given speed, and conversely, the ³⁰ shorter the tube, the less power is required. If the air-propelling mechanism operates at the same speed all the time, neglecting leakage, the amount of power required to drive same will increase as the pressure ³⁵ increases and decrease as the pressure decreases.

In the system herein shown and described, the air-propelling mechanism is driven at practically a uniform speed and ⁴⁰ the controlling mechanism and arrangement of tube lines embodied in my invention throws into circuit only that portion of the tube system which is despatching carriers, thereby saving the power which ⁴⁵ would be required to drive the air through the whole system all the time.

This system is composed of three lines radiating from a central station, but I do not limit myself to any particular number of ⁵⁰ lines.

In the accompanying drawings which illustrate a construction embodying my invention, Figure 1 represents a complete system of three branches covering everything ⁵⁵ except the air-propelling mechanism and in

a position when no carriers are being despatched. Fig. 2 is a similar view but showing the position of the various parts while a carrier is being despatched in one of the branches. Fig. 3 is a longitudinal section ⁶⁰ of the electric controlling mechanism. Fig. 4 is a lateral section of same.

Like letters of reference refer to like parts throughout the several views.

The tube A leads to the air-propelling ⁶⁵ blower P which as before explained is run at a practically uniform speed, thereby giving to the air practically a uniform speed regardless of the degree of exhaustion. The branch lines B, B', B² are connected in series at the central station by the tubes A', A². Each of these branch lines B, B', B² is provided with a by-pass tube C, C', C² respectively, and in each by-pass tube is located a shut off valve D, D', D² respectively, controlled by the solenoids D³, D⁴, D⁵. The branch lines B, B', B² are made up of out-going tubes B³, B⁴, B⁵ respectively and return tubes B⁶, B⁷, B⁸ respectively. The despatching end of the out-going tube B³ is an open end E, while the despatching ends of the outgoing tubes B⁴, B⁵ are provided with flap valves E', E², and the despatching ends of the return tubes B⁶, B⁷, B⁸ are provided with flap ⁷⁰ valves E³, E⁴, E⁵. The receiving ends of both the outgoing tubes B³, B⁴, B⁵ and the return tubes B⁶, B⁷, B⁸ are provided with flap valves E⁶, E⁷, E⁸, E⁹, E¹⁰, E¹¹ and goose-neck receiving scoops F, F', F², F³, ⁷⁵ F⁴, F⁵ respectively. At the outside terminus of the branch lines B, B', B² are cross over tubes C⁸, C⁴, C⁶; and just inside the despatching ends of the outgoing tubes B³, B⁴, B⁵ and the returning tubes B⁶, B⁷, B⁸ ⁸⁰ are fingers G, G', G², G³, G⁴, G⁵ pivoted at the points H, H', H², H³, H⁴, H⁵ and provided at their opposite ends with the switch arms J, J', J², J³, J⁴, J⁵ which make contact with the switch plates J⁶, J⁷, J⁸, J⁹, ⁸⁵ J¹⁰, J¹¹ when carriers are despatched in the respective tubes.

K is an electric battery for operating the controlling mechanism of the entire system. The electric conductors are represented by ⁹⁰ numerals.

X is a carrier.

In Figs. 3 and 4 which show the details of one of the controlling mechanisms, D' is the valve, D⁴ the solenoid, L ¹⁰⁵ 110

the armature which is drawn up into the solenoid D^4 when same is electrically excited. L' is the valve stem connecting the armature with the valve D' , and L^2 is the 5 piston rod which connects the piston L^3 with the lower end of the valve D' . The piston L^3 is provided with ports L^4 which are closed by the clapper L^5 when the piston L^3 is descending in the cylinder L^6 and 10 when the piston is rising the clapper L^5 drops down against the shoulder L^7 thereby opening the ports L^4 and permitting the piston L^3 to move freely in the cylinder L^6 . The upper portion of the cylinder wall is 15 smooth, but the lower end is provided with longitudinal channels L^8 so that there will be no cushioning effect during the latter part of the downward travel of the piston L^3 . A by-pass duct M connects the upper 20 end with the lower end of the cylinder L^6 and this by-pass duct M is provided with a needle valve M' which is for the purpose of regulating the amount of stricture in the by-pass duct M thereby predetermining the 25 speed with which the piston L^3 shall descend through the smooth bore portion of the cylinder L^6 .

The operation is as follows: when no carriers are being despatched, the air in the 30 outgoing and return tubes is still and the current of air entering the open end E of the outgoing tube B^8 , passes through the by-pass tube C to the tube A , thence through the tubes C' , A^2 , C^2 and A respectively and 35 to the air-propelling blower P . As the length of tube through which the air passes when no carriers are being despatched is very short, there is very little friction and therefore very little power required to drive 40 same. When a carrier is inserted in any of the tubes at the despatching end such as the despatching end of the return tube B^7 , as shown in Fig. 2, it presses the finger G^4 into the position shown in Fig. 2 thereby 45 making an electrical connection between the switch arm J^4 and the switch plate J^{10} and completing the electrical circuit from the battery K through the conductors 1, 2, 3, the solenoid D^4 and the conductors 4, 5 50 and 6, and the current passing through the solenoid D^4 excites it and thereby causes it to draw the armature L (Fig. 5) up into it which brings the valve D' into its uppermost position and this closes the passage in 55 the by-pass pipe C' so that the current of air is caused to travel through the outgoing tube B^4 , the cross-over tube C^4 and the return tube B^7 . This current of air propels the carrier through the return tube 60 B^7 to the receiving end where it strikes the flap valve E^{10} opening same by its impact and discharging into the goose-neck scoop F^4 . As soon as the carrier X passes the finger G^4 , said finger is returned by suitable 65 means, such as a spring or weight, to the

position shown in Fig. 1, and the electric circuit is thus broken and the solenoid D^4 ceases to exert an upward influence on the armature L . The valve D' and the armature L with the other parts attached to same are of such weight that immediately the effect of the electrically excited solenoid is removed, they begin to descend of their own weight but are prevented from dropping quickly by the cushioning effect of the piston L^3 on the air or any other fluid with which the cylinder L^6 may be filled. The piston L^3 descends only as fast as it can force the fluid in the portion of the cylinder under it into the portion of the cylinder above it through the needle valve M' which is adjusted to govern the time of descent so that the valve D' is kept closed long enough to give the carrier X time to be propelled from one end of the branch line B' to the opposite end of same. It will be noticed that the valve D' is oval in shape. This is so it will keep the by-pass tube C' closed during its descent until the piston L^3 reaches the point in the cylinder L^6 where the channels L^8 begin and from this point to the lower end of its travel, there is no cushioning effect and the valve drops suddenly thereby opening the by-pass pipe C' quickly. Should a second carrier be despatched while the first is in transit, the valve D' will be drawn from its intermediate position back to its starting position thereby starting the regulation of the time interval over again and at the moment the last carrier is despatched, which gives the last carrier time to get out of the tube before the valve D' opens the by-pass C' thereby shutting off the branch B' .

It will be understood that the times of descent of the various pistons is predetermined by the adjustment of the needle valves so that a longer line will be given a proportionately longer time, etc.

Having thus described the nature of my invention and set forth a construction embodying the same, what I claim as new and desire to secure by Letters Patent of the United States is:

1. In pneumatic despatch tube apparatus, 115 a plurality of transmission tube systems with each system comprising sending and return tubes communicating at their outer ends, a blower, an air-conduit leading to said blower common to all the transmission tube sys- 120 tems and in series communication with the inner ends of the sending and return tubes of each system, and means for switching the flow of air from the common conduit through the sending and return tubes of any one of 125 the transmission tube systems.

2. In pneumatic despatch tube apparatus, a plurality of transmission tube systems with each system comprising sending and return tubes communicating at their outer 130

ends, a blower, an air-conduit leading to said blower common to all the transmission tube systems and in series communication with the inner ends of the sending and return tubes of each system, means for switching the flow of air from the common conduit through the sending and return tubes of any one of the transmission tube systems, and means for timing and limiting the flow 10 of air through any one of the transmission tube systems to the interval necessary for the transmission of a carrier through the system in operation.

3. In pneumatic despatch tube apparatus, 15 a plurality of transmission tube systems with each system comprising sending and return tubes communicating at their outer ends, a blower, an air-conduit leading to said blower common to all the transmission 20 tube systems and in series communication with the inner ends of the sending and return tubes of each system, and electro-magnetic means operating to switch the flow of air from the common conduit through any 25 one of the transmission tube systems.

4. In pneumatic despatch tube apparatus, 30 a plurality of transmission tube systems with each system comprising sending and return tubes communicating at their outer ends, a blower, an air-conduit leading to said blower common to all the transmission tube systems and in series communication with the inner ends of the sending and return tubes of each system, electro-magnetic 35 means operating to switch the flow of air from the common conduit through any one of the transmission tube systems, and means for timing the operation of the electro-magnetic means so as to limit such operation to 40 the interval necessary for the transmission of a carrier through the system in operation.

5. In pneumatic despatch tube apparatus, 45 a plurality of transmission tube systems with each system comprising sending and return tubes communicating at their outer ends, a blower, an air-conduit leading to said blower common to all the transmission tube systems and in series communication with the inner ends of the sending and return 50 tubes of each system, and means actuated by the insertion of a carrier in a tube of any of the transmission tube systems for switching the flow of air from the common conduit through the system in the tube of which the carrier has been placed.

6. In pneumatic despatch tube apparatus, 55 a plurality of transmission tube systems with each system comprising sending and

return tubes communicating at their outer ends, a blower, an air-conduit leading to 60 said blower common to all the transmission tube systems and in series communication with the inner ends of the sending and return tubes of each system, means actuated by the insertion of a carrier in a tube of any 65 of the transmission tube systems for switching the flow of air from the common conduit through the system in the tube of which the carrier has been placed, and means for timing and limiting the flow of air through the 70 system so put in operation to the interval necessary for the transmission of the carrier through such system.

7. In pneumatic despatch tube apparatus, 75 a plurality of transmission tube systems with each system comprising sending and return tubes communicating at their outer ends, a blower, an air-conduit leading to said blower common to all the transmission tube systems and in series communication 80 with the inner ends of the sending and return tubes of each system, and electro-magnetic means energized by the insertion of a carrier in the tube of any of the transmission tube systems to switch the flow of air 85 from the common conduit through the system in which the carrier has been placed to propel the carrier through such system.

8. In pneumatic despatch tube apparatus, 90 a plurality of transmission tube systems with each system comprising sending and return tubes communicating at their outer ends, a blower, an air-conduit leading to said blower common to all the transmission tube systems and in series communication 95 with the inner ends of the sending and return tubes of each system, electro-magnetic means energized by the insertion of a carrier in the tube of any of the transmission tube systems to switch the flow of air from the 100 common conduit through the system in which the carrier has been placed to propel the carrier through the same, and means for timing the operation of the electro-magnetic means to limit the flow of air through 105 the system in which the carrier has been placed to the interval necessary to propel the carrier through such system.

In testimony whereof, I have signed my name to this specification in the presence of 110 two subscribing witnesses, this seventeenth day of July A. D. 1908.

CHARLES F. STODDARD.
